UNITED STATES PATENT OFFICE.

CARRIE L. HURLBUT, OF WASHINGTON, DISTRICT OF COLUMBIA.

PLAITING APPARATUS.

SPECIFICATION forming part of Letters Patent No. 629,255, dated July 18, 1899.

Application filed April 17, 1899. Serial No. 713,362. (No model.)

To all whom it may concern:

Be it known that I, CARRIE L. HURLBUT, a citizen of the United States, residing at Washington, in the District of Columbia, have invented certain new and useful Improvements in Plaiting Apparatus, of which the following is a specification.

My present invention relates to plaiting-machines, the construction and advantages of which will be hereinafter set forth, reference being had to the annexed drawings, wherein—

Figure 1 is a top plan view of the device; Fig. 2, a transverse vertical sectional view; Fig. 3, a perspective view of a portion of the apparatus, the parts being shown in a separated condition; Fig. 4, a perspective view of the gage or knife, and Fig. 5 a perspective view of a modification.

The object of my invention is to provide a simple and effective plaiter, one which will be strong and easily constructed, yet productive of good results in its use.

Referring to the drawings, A denotes the main side bars or members, provided with a lateral wing or projection B, having a groove or channel C, extending along or formed in the upper face thereof adjacent to the upright wall D of the side bar. The upper face of the side bar is formed with a series of transverse grooves or seats E, spaced at equal distances from each other, as is most clearly indicated in Fig. 3.

F indicates the cross-bars or slats, preferably rectangular in cross-section. Each end of the bar is first bent down, forming a vertical section G, and then the extreme end is bent out horizontally or parallel with the main body, as at H, forming, as it were, a double hook. The upright portion G is of such length as to extend from the bottom of the recesses or seats E down to the slot or channel C, while the arm H is of a length equal to the width of said channel. The cross-bars or slats are seated in the slots or recesses E, as indicated in Figs. 2 and 3, and a side bar or strip I is employed for clamping them in place. Said bar or strip, as will be seen more particularly upon reference to Fig. 3, is provided with a series of vertical grooves or channels J, which when the strip is in place fit over and around the vertical members G of the cross-bars or slats. It will also be noted that the lower

edge of said bar or strip fits down over the projecting ends H and bears directly on the upper face of the projecting wings B of member A. A suitable number of small bolts K or other equivalent fastening devices are passed through the main side bars A and the retaining-strips I to securely hold the parts together. It is manifest that when the ends of the cross-bars are seated in the grooves and the retaining-strips secured in their position the parts are all closely and firmly held together, making a very rigid and yet at the same time a relatively light structure.

Instead of forming the vertical grooves or seats for the upright portions G of the cross-bars in the side retaining-strip, said grooves or seats may be formed in the main side bar or member A, as is indicated in Fig. 5, in which case the side face of the retaining-strip will be made plain.

From the foregoing description it will be noted that the upper face of the cross-bars, the upper face of the member A, and the upper faces of the retaining-strips are all flush. This is a point of manifest advantage, for the reason that it presents a perfectly flat surface when the machine or device is turned over on an ironing-board or the like after the material has been worked in between the slats, and thus holds the work in place when it is ironed down upon the under side of the cross-bars. Where the side bars, or, in fact, any portion of the device, project above the cross-bars it is manifest that this could not be done.

In Fig. 4 I have shown a gage or folder for forcing the material down between the cross-bars. It is made of a single piece of metal, bent to form, having a laterally-projecting wing L and two blades M and N, the former being wider or deeper than the latter, and consequently making a wider or deeper plait. Wing L serves, of course, as a stop to limit the downward movement of the folder.

Having thus described my invention, what I claim is—

1. In a plaiting apparatus, the combination of two side bars or members, provided with a series of cross-slots or seats formed in their upper faces, and a groove or channel C extending lengthwise thereof; a series of bars or slats provided with reversely-hooked ends seated within said slots and channel substan-

tially as described; and a retaining-strip secured to said side bars over the ends of the slats.

2. In a plaiting apparatus, the combination 5 of two side bars or members, provided with a series of cross-slots or seats formed in their upper faces, and a groove or channel C extending lengthwise thereof to one side of said seats and in a plane below the same; a series 10 of bars or slats provided with downwardly and outwardly projecting ends G, H; and a retaining-strip secured to said side bars over the ends of the slats.

3. In a plaiting apparatus, the combination 15 of two side bars or members A, provided with a series of cross-slots or seats E; a channel C extending lengthwise of said bars to one side of and in a plane lower than said slots or seats; a series of slats or cross-bars provided

with reversely-hooked ends G, H; and a retaining-strip I provided with a series of vertical grooves or seats, said strip adapted to be secured to the side bars over the ends of cross-bars, substantially as described.

4. In a plaiting apparatus, the combination 25 of two side bars; a series of cross-bars or slats seated in the upper faces thereof; and independent retaining-strips for said slats secured to the outer faces of the side bars, said side bars, slats and retaining-strips being flush 30 upon their uppermost faces, substantially as and for the purpose described.

In witness whereof I hereunto set my hand in the presence of two witnesses.

CARRIE L. HURLBUT.
